UNITED STATES PATENT OFFICE

129,425

DESIGN FOR A BASE HOUSING FOR FLOOR MAINTENANCE MACHINES

William E. Holt, Oakland, Calif.

Application June 19, 1941, Serial No. 101,558

Term of patent 7 years

To all whom it may concern:

Be it known that I, William E. Holt, a citizen of the United States, residing at Oakland, in the county of Alameda and State of California, have invented a new, original, and ornamental Design for a Base Housing for Floor Maintenance Machines, of which the following is a specification, reference being had to the accompanying drawing, forming part thereof.

Fig. 1 is a side elevation of a base housing for floor maintenance machines, showing my new design;

Fig. 2 is a plan view thereof; and
Fig. 3 is a rear view thereof.

I claim:

The ornamental design for a base housing for floor maintenance machines, as shown.

WILLIAM E. HOLT.
